Atty.

UNITED STATES PATENT OFFICE.

JAMES ROBERT COE, OF ANSONIA, CONNECTICUT.

SPINNING-RING.

SPECIFICATION forming part of Letters Patent No. 783,681, dated February 28, 1905.

Original application filed July 16, 1904, Serial No. 216,905. Divided and this application filed November 18, 1904. Serial No. 233,325.

To all whom it may concern:

Be it known that I, JAMES ROBERT COE, a citizen of the United States, residing at Ansonia, in the county of New Haven, in the State of Connecticut, have invented certain new and useful Improvements in Spinning-Rings, of which the following is a specification.

The subject-matter of this invention is a sheet-metal spinning-ring, and the present application is a division of my application Serial No. 216,905, which covers the manufacture of the same.

Spinning-rings have been heretofore produced in various ways both from solid stock and from sheet metal, but have been subject to various defects caused by their structural form or the steps necessary to produce the same.

It is the object of the present invention to produce a double-flanged ring formed from sheet metal by steps, which while inexpensive and unobjectionable in themselves produce a novel structural form possessing the many requirements of a commercial ring.

In the drawings, in which like letters of reference indicate corresponding parts throughout, Figures 1, 2, and 3 represent a double-flanged ring in three steps in its manufacture. Figs. 4, 5, and 6 represent a modification of a double-flanged ring.

R indicates the body of the ring, R' the flange of different diameter, and r' indicates the curved shoulder between the ring and the flange. Inasmuch as the value of the ring itself depends upon its structure, and its structure in turn is the result of the several structural steps of its manufacture, a brief description of the same will be first given.

A tube of metal is first formed in any desirable manner, preferably by drawing up a cup from a flat disk and removing the bottom from the same. This tube is then treated so as to produce an area which is to form the body of the spinning-ring, and an area or areas to form the flanges of the spinning-ring, the latter being of a different diameter from that of the body portion. In case the seam is to be on the outside of the ring the flanged portions are of a smaller diameter than the body portion, whereas in case the seam is

to be internal the flanged portions are larger than the body portion. The production of these areas of different diameter may obviously be brought about in a number of different ways; but I have found that the ring 55 may be most successfully rolled on a loose mandrel to secure this result.

The shoulder between the two portions is formed with a circular bend, so as to form a portion of the complete circle, which the cross-section of the flange will show when bent down against the body portion. By thus forming the shoulder the body of the ring is brought centrally of the flange, and the latter when flattened and compressed is given a form of maximum rigidity and finish.

The flange portion is then turned over to meet the central or body portion—that is, if the body portion is of a smaller diameter than the flanged portion the latter is turned inward, 70 while if the body portion is larger the flanged portion is turned outward. The tubular flange is then compressed and flattened to give the shape desired in the finished ring.

The structure of this ring may be varied, 75 and certain of the steps through which it is brought may be modified, and other types of spinning-rings may be produced of the general flanged structure set forth herein.

What I claim, and desire to secure by Letters Patent, is—

1. A spinning-ring formed of sheet metal having a tubular body portion and double flanges at each end, said flanges each comprising an inwardly-projecting overfolded 85 flange and an outwardly-projecting underfolded flange.

2. A spinning-ring formed of sheet metal having a tubular body portion and double flanges at each end, said flanges each comprising an inwardly-projecting overfolded flange and an outwardly-projecting underfolded flange with the edge joint disposed at the exterior of the ring and inwardly abutting against said body portion. 95

3. A spinning-ring formed of sheet metal having a body portion and a flat-topped traveler-race at each end, formed by a flange inwardly projecting from said body portion and doubled over upon itself and extended to form 100

an outwardly-extending flange which is doubled thereunder and abutted against the body portion.

4. A spinning-ring formed of sheet metal having a tubular body portion and a double-flanged traveler-race at each end, said flanges being each formed with a double thickness of metal throughout.

5. A spinning-ring formed of sheet metal having a tubular body portion and inwardly and outwardly projecting flanges at each end, each flange consisting of a double fold of the metal.

6. A spinning-ring formed of sheet metal

having a tubular body portion and a flattened double flange at each end thereof, said double flanges comprising a laterally-bent portion, a portion doubled thereover to complete said flange, continued to form the adjoining flange and returned thereunder to abut against the body portion.

In testimony whereof I affix my signature in presence of two witnesses.

JAMES ROBERT COE.
